AUDION AMPLIFIER

Application filed June 29, 1925. Serial No. 40,435.

This invention relates to audion amplifiers and particularly to amplifier networks arranged to control or to eliminate retroactive currents through the grid-plate capacity.

5 It has been proposed to construct an amplifier network as an alternating current Wheatstone bridge in which the input and the output circuits of the amplifier stage comprise conjugate arms which are electrically 10 isolated so far as alternating currents are concerned.

An object of this invention is to provide an audion amplifying stage in which retroaction from output circuit upon input circuit 15 may be made to vary in predetermined fashion with the frequency, may be made substantially independent of frequency, or may be suppressed over a wide range of frequencies. Specifically an object of the invention is to 20 provide an audion circuit in which input and output circuits are made conjugate arms of an alternating current Wheatstone bridge which has three substantially pure capacity balancing arms and a fourth balancing arm 25 comprising a composite impedance the effective capacity of which is a function of the frequency.

Specific embodiments of my invention are illustrated in the accompanying drawings in 30 which

Fig. 1 is a circuit diagram of an audion amplifying stage constructed in accordance with my invention;

Fig. 2 is a bridge diagram of the impedance 35 elements of the alternating current network of Fig. 1;

Fig. 3 is a circuit diagram of an audion detector which due to the so-called "regenerative effect" also acts as a radio frequency 40 amplifier; and

Fig. 4 is a diagram of a cascade amplifier.

As will be seen from Fig. 1, the output circuit of the stage is arranged in the usual manner, and is there shown as comprising a coil 45 L which may be the primary of a coupling transformer for the succeeding stage. The input circuit is shown as an impedance L_1 shunted by a variable condenser C, but the nature of the input circuit is not material. 50 It is to be noted, however, that the input cir-

cuit is not connected across the input terminals G, F of the tube T, but is connected across the terminals G, 2, which terminals I designate as the input terminals of the amplifying stage. The path from the lower input terminal 2 of the stage to the lower tube terminal F is provided by a condenser C_b shunted by an impedance L_2 . This path 2F forms one arm of the alternating current Wheatstone bridge and will be designated as 55 the "composite arm" to distinguish from the three capacity arms C_m , C_a and C_c , which comprise, respectively, the inherent grid-plate capacity of the tube, an external capacity connected between the plate P and the lower stage terminal 2, and the capacity between the grid and filament terminals. As indicated in Fig. 1, the capacity C_c between the grid and filament terminals may be composed of the 60 inherent tube capacity C_g plus an external capacity C_t which is shunted across the tube capacity. The external capacity may be variable, if desired, for purposes of adjustment, but this control is not essential. In fact, the external capacity C_t may be eliminated entirely and the balance may be obtained by a proper choice of the constants of the other arms of the bridge. The plate battery may be shunted by a large capacity C_B to provide a by-pass for the alternating current. 65

The network of Fig. 1 has the form of a Wheatstone bridge as will be evident from an inspection of Fig. 2. It is apparent that the condition for balance is given for all frequencies greater than the resonant frequency 70 of the composite arm, 75

$$\frac{1}{2\pi\sqrt{L_2C_b}},$$

80 by the equation:

$$\frac{C_a}{C_m} = \frac{C'_b}{C_c} \quad (1),$$

85 where C'_b is the effective capacity of the composite arm L_2C_b .

The arms C_m and C_a are pure capacity arms; hence their ratio in equation (1) is invariant with frequency. C_c can be made a 90 95 100

pure capacity by properly biasing the grid of the audion, and the effective capacity of the composite arm may be substantially independent of the frequency or it may be made to vary with the frequency, as desired. It is shown both by experiment and by elementary circuit theory, that for all frequencies substantially greater than the value

$$10 \quad \frac{1}{2\pi\sqrt{L_2 C_b}}$$

the effective capacity C'_b of the arm F_2 is given approximately by the equation:

$$15 \quad C'_b = C_b - \frac{1}{\omega^2 L_2} \quad (2)$$

where $\omega = 2\pi \times$ frequency. Thus if the inductance of the choke coil L_2 is so chosen that its inductive reactance ωL_2 is large compared with the capacitive reactance

$$\frac{1}{\omega C_b}$$

of the capacity C_b over a given range of frequencies, the effective capacity C'_b will be closely equal to C_b and will be practically independent of frequency over this range. Explicitly, suppose that in a given range of frequencies L_2 is made so large that L_2 is greater than

$$1000 \left(\frac{1}{\omega C_b} \right)$$

throughout the range. Then according to (2) the effective capacity C'_b must be between the value C_b and the value $0.999 C_b$ throughout this range; in other words it is for all practical purposes constant and equal to C_b . The bridge can therefore be balanced as with four capacity arms and the balance will be maintained without appreciable variation throughout this range.

This is the condition of my circuit appropriate to an audion amplifying stage in which retroactive currents and regeneration are completely suppressed over a band of frequencies. For instance if I wish to suppress retroactive currents by a complete bridge balance over the band of wave lengths 200 to 1000 meters ($\omega = 9.42 \times 10^6$ to 1.88×10^6) with a given audion, I may make C_b of the order of magnitude 200 micromicrofarads, L_2 equal to or greater than 1.4 henries, select C_1 and C_a so that Equation (1) is satisfied, using the value 200×10^{-12} for C'_b , and the bridge circuit is completely balanced, to an accuracy of one part in one thousand, with consequent suppression of retroactive currents, over this specified wave band. I have found it convenient, when a balance substantially independent of frequency over the whole range of radio frequencies is desired, to use as L_2 the secondary winding of an ordinary commercial audio frequency trans-

former. C_b may comprise only the distributed capacity of these windings or may include an external condenser as well. This use of an audio frequency secondary L_2 is convenient when my invention is applied to a circuit of the so called "reflex" type, in which the grid circuit of an audion is fed simultaneously from an audio-frequency transformer and a radio-frequency transformer connected in series.

The use of the choke coil L_2 across the arm C_b not only permits the reflexing of the balanced stage but has the additional and important function of placing the direct current potential of the grid at a predetermined value for preventing extraneous noises and blocking in the audion. So far as the construction of a stage which is balanced independent of frequency is concerned, the presence of the coil L_2 is not essential; but for the satisfactory reception of signals the choke is of decided value, particularly when several stages are cascaded.

The invention is not limited however to amplifiers in which the inductance L_2 and capacity C_b are so related that the effective capacity C'_b is practically invariant with frequency. By a proper design of these parts it is possible to secure a substantially constant amplification at all wave lengths even though the coupling transformers are of the type which normally result in a decrease in the amplification rate with increasing wave length. At the higher wave lengths it is possible to operate with a degree of unbalance which would cause sustained oscillations or objectionable reaction at the lower ranges. The unbalance may be so chosen that a predetermined regenerative effect supplements the non-regenerative amplification as the latter falls off at the lower frequencies.

From Equation (2) it will be evident that the effective capacity of the composite arm will vary rapidly with the frequency when the inductive reactance $L_2 \omega$ is greater than, but comparable with, the capacity reactance

$$\frac{1}{C'_b \omega}$$

The following specific example may be cited:

If L_2 is made equal to 500 microhenries and C_b made 200 micromicrofarads, the effective capacity C'_b of the arm to F is 177 micromicrofarads at 200 meters, 110 micromicrofarads at 400 meters, and above 596 meters the reactance of this arm is no longer capacitive but inductive. Thus if the arms C_a and C_c were chosen to provide a balance at 200 meters, retroaction from the plate circuit to the grid circuit would increase progressively with the wave length above this point. At wave lengths above 596 meters not even an approximate balance occurs, since one arm of the bridge is no longer capacitive, and if the output circuit is tuned or has a large induc-

tive component, strong regeneration occurs.

This feature of my invention can be applied with advantage in a circuit which is primarily regenerative, such as an audion detector having a variable inductance in the plate circuit. Fig. 3 shows such a circuit, which is the conventional Armstrong regenerative detector having a plate variometer L_3 which causes retroaction through the grid-plate circuit with consequent regenerative increase in the tuned input circuit L_1C . In accordance with my invention a balancing network comprising C_a , C_1 and the composite arm L_2C_b is added to this circuit. At frequencies for which the condition of balance is satisfied no regeneration can occur for any value of inductance L_3 in the plate circuit. On the other hand, when the bridge is unbalanced, more or less regeneration occurs, depending upon the extent of unbalance and upon the size of L_3 . It is possible so to adjust the capacities of the bridge arms that a variation in the balance condition with wave length occurs which produces maximum regeneration over a substantial band of wave lengths without altering the value of L_3 . This effect is impossible in an ordinary regenerative circuit where, as is well known, it is necessary to increase the plate circuit inductance progressively with increasing wave length in order to maintain the maximum regeneration.

As will be apparent from Fig. 4, stages such as illustrated in Fig. 1 may be cascaded in the usual manner when the inductance L_1 of the first stage is coupled to an antenna circuit AG and the plate inductance L of one stage and the input inductance L_1 of the succeeding stage take the form of the primary and the secondary, respectively, of a coupling transformer.

The invention is not limited to the specific circuit details illustrated in the accompanying drawings nor to the particular constants herein specified, as the arrangement of the bridge circuit and the relative values of the elements employed may be varied within wide ranges without departing from my invention.

Obviously a complete balance or the desired approximation thereto may be obtained by varying one or more of the quantities appearing in Equation (1).

So far as I am aware it is broadly new to provide an audion network in which the direct current potential of the grid is fixed with respect to the filament, and in which the input and output circuits are connected across conjugate terminals of an alternating current Wheatstone bridge having one or more balancing arms whose impedances are variant with frequency, and of which the remaining balancing arms are substantially pure capacities. My invention therefore contemplates all arrangements of this type whether or not the bridge is balanced and hence non-

regenerative over a substantial range of frequencies, or whether it is unbalanced and hence regenerative for a portion of the range of frequencies at which the amplifier is adapted to operate.

I claim:

1. In an audion amplifier network arranged at a Wheatstone bridge which may be balanced to control retroactive currents, input and output circuits of the amplifier stage forming the respective conjugate arms of the bridge, and four balancing arms, three of said arms comprising substantially pure capacities and the fourth arm comprising a composite impedance having an effective capacity which is a function of the frequency. 70

2. In an amplifier, a three-electrode audion, input and output circuits therefor adapted to form conjugate arms of a Wheatstone bridge, three points of the said bridge being defined by the grid, plate and filament terminals of said audion, and balancing arms connecting the plate and the filament terminals respectively with a fourth bridge point, the impedances comprising three of said arms being capacities whose respective reactances at varying frequencies are substantially those of fixed capacities, and the impedance of the fourth arm being composite and having a reactance which, within predetermined limits within the frequency range of the amplifier, varies with frequency at a rate substantially different from that of a fixed capacity. 85

3. In an audion amplifier, an alternating current Wheatstone bridge network comprising conjugate arms which form, respectively, the input and output circuits of the amplifier stage, three balancing arms having the form of substantially pure capacities and a fourth arm comprising a composite impedance having an effective capacity which is a function of the frequency. 100

4. An audion amplifier stage the impedance mesh of which is arranged in the form of an alternating current Wheatstone bridge of which the input and output circuits of the amplifier stage form conjugate arms, the balancing arms of said bridge comprising substantially pure capacity between grid and plate of the audion tube, substantially pure capacity between grid and filament of said audion tube, and two impedances connected

in series in the plate circuit of said audion tube, one of said impedances comprising a substantially pure capacity and the other of said impedances comprising a capacity shunted by an inductance, one terminal of said input circuit being connected to the grid of said audion tube and the other terminal of said input circuit being connected to a point intermediate said two impedances in the plate circuit of said audion tube. 110

5. In an audion amplifier, an alternating current Wheatstone bridge network comprising conjugate arms which form, respectively,

the input and output circuits of the amplifier stage, three balancing arms having the form of substantially pure capacities, and a fourth balancing arm comprising a capacity shunted by an inductance, whereby the effective capacity of said arm is a function of the frequency.

6. In an audion amplifier network arranged as a Wheatstone bridge which may be balanced to control retroactive currents, input and output circuits of the amplifier stage forming the respective conjugate arms of the bridge, and four balancing arms, three of said arms comprising substantially pure capacities and the fourth arm comprising a parallel inductance-capacity circuit of which the reactance of the inductive branch is comparable with, but greater than, the reactance of the capacitive branch, whereby the effective capacity of the composite impedance is a function of the frequency.

In testimony whereof, I affix my signature.
LEWIS M. HULL.
